UNITED STATES PATENT OFFICE.

MARY A. FISHER, OF NEW ROCHELLE, NEW YORK.

DESIGN FOR A SPOON.

SPECIFICATION forming part of Design No. 22,438, dated May 16, 1893.

Application filed April 18, 1893. Serial No. 470,890. Term of patent 7 years.

To all whom it may concern:

Be it known that I, MARY A. FISHER, of New Rochelle, in the county of Westchester and State of New York, have invented a novel and ornamental Design for Souvenir Spoons; and I do hereby declare that the following is a full and exact description thereof, reference being had to the accompanying drawings, making a part of this specification.

10 The object of my invention is to produce a novel and pleasing design for the ornamentation of spoons, with especial reference to the obverse and reverse of both the handle and the bowl.

15 The accompanying drawings present, in Figures 1 and 2 respectively, views of the obverse and reverse of a spoon ornamented with my design.

20 The obverse of the upper end of the handle bears a portrait bust of a man having upon his head a flat cap and upon his shoulders a garment with high collar; while upon the reverse of the same is represented a bell supported from a cross-beam. The obverse of

the bowl bears a scroll and a coat-of-arms 25 with two sprays of myrtle, the coat-of-arms showing three fleurs de lis and a ship. Upon the reverse of the bowl is represented a rude edifice with an overshadowing tree. The handle, between the upper end and the bowl, has 30 a spray of myrtle on the obverse and on the reverse and bears the representation of a ribbon wound about it in an open spiral.

I claim as my invention—

1. In a design for a souvenir spoon, the obverse, substantially as shown and described. 35
2. In a design for a souvenir spoon, the reverse, substantially as shown and described.
3. The design for a souvenir spoon, substantially as shown and described. 40

In testimony whereof I have signed my name to this specification in the presence of two subscribing witnesses.

MARY A. FISHER.
